FROZEN CONFECTION

Lester W. Von Losberg, New York, N. Y., assignor to Joe Lowe Corporation, New York, N. Y., a corporation of Delaware

Application November 20, 1948, Serial No. 149,744

Term of patent 14 years

(Cl. D82—2)

To all whom it may concern:

Be it known that I, Lester W. Von Losberg, a citizen of the United States, residing in New York, in the county of New York and State of New York, have invented a new, original, and ornamental Design for Frozen Confection, of which the following is a specification, reference being had to the accompanying drawing, forming a part thereof, in which:

The frozen confection is characterized by its rounded top and the distinctive arrangement of the V-shaped indentations.

I claim:

The ornamental design for a frozen confection, as shown and described.

LESTER W. VON LOSBERG.
